US00D961540S

(12) **United States Design Patent** (10) **Patent No.:** **US D961,540 S**
(45) **Date of Patent:** **** Aug. 23, 2022**

(54) **MOBILE PHONE**

(71) Applicant: **LG ELECTRONICS INC.**, Seoul (KR)

(72) Inventors: **Seunghoon Ryu**, Seoul (KR); **Youngho Kim**, Seoul (KR)

(73) Assignee: **LG ELECTRONICS INC.**, Seoul (KR)

(**) Term: **15 Years**

(21) Appl. No.: **29/753,220**

(22) Filed: **Sep. 30, 2020**

(30) **Foreign Application Priority Data**

Jun. 11, 2020 (KR) 30-2020-0026279

(51) **LOC (13) Cl.** 14-03

(52) **U.S. Cl.**

USPC ..... **D14/138 G**; D14/138 C

(57) **CLAIM**

The ornamental design for a mobile phone, as shown and described.

DESCRIPTION

FIG. 1 is a front perspective view of the mobile phone showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is a back perspective view thereof.

The broken lines depict portions of the mobile phone that form no part of the claimed design.

1 Claim, 8 Drawing Sheets
